UNITED STATES PATENT OFFICE.

WILLIAM MARRETT, OF TOLEDO, OHIO, ASSIGNOR TO THE LIBBEY GLASS COMPANY, OF TOLEDO, OHIO, A CORPORATION OF OHIO.

DESIGN FOR A CUT-GLASS VESSEL.

SPECIFICATION forming part of Design No. 36,276, dated April 7, 1903.

Application filed February 10, 1903. Serial No. 142,811. Term of patent 7 years.

To all whom it may concern:

Be it known that I, WILLIAM MARRETT, a citizen of the United States, residing at Toledo, in the county of Lucas and State of Ohio, have invented and produced a new, original, and ornamental Design for a Cut-Glass Vessel, of which the following is a specification, reference being had therein to the accompanying drawings, in which—

10 Figure 1 is a perspective view of the inverted vessel, and Fig. 2 is a bottom plan view thereof.

The design is applicable to various vessels of cut-glass ware.

15 The bottom portion is ornamented by radial cuttings A, producing a star-shaped pattern. B represents flutes extending radially from this central pattern, and these flutes are

separated from each other by bars of ornamentation C. The ornamentation on the bars 20 C is varied, as shown at C', C², C³, C⁴, C⁵, C⁶, C⁷, and C⁸. The periphery is escalloped, as shown at D.

The leading feature of the design consists in a vessel having a series of radially-extending 25 plain flutes separated from each other by bars of ornamentation.

What I claim as my invention is—

The ornamental design for a cut-glass vessel substantially as described. 30

In testimony whereof I affix my signature in presence of two witnesses.

WILLIAM MARRETT.
